UNITED STATES PATENT OFFICE.

LEVERETT W. TIFFANY, OF WINSTED, CONNECTICUT.

ASSORTING MACHINE.

Application filed September 14, 1925. Serial No. 56,155.

This invention relates to an assorting machine of improved construction and specifically stated aims to provide a device of this character particularly adapted for use in the assorting and packaging of pins.

It is an object of the invention to provide a machine of this type which in certain respects will present an improved construction over that embodied in my co-pending application, Serial No. 717,678, filed June 4, 1924, in that the articles being assorted will be more expeditiously and efficiently handled and distributed and in that, further, the likelihood of error will be reduced to a minimum.

An additional object is that of providing an assorting machine which will efficiently perform the purposes for which it is intended, and which will also be economically and readily manufactured and easily assembled.

Other objects of the invention will in part be obvious and will in part appear hereinafter.

The invention accordingly comprises the features of construction, combination of elements and arrangement of parts which will be exemplified in the construction herein-after set forth, and the scope of the application of which will be indicated in the claims.

For a fuller understanding of the nature and objects of the invention reference should be had to the following detailed description taken in connection with the accompanying drawing, in which:

Figure 1 is a plan view of one form of machine embodying the improved construction of the present invention, certain of the parts being broken away to disclose the underlying construction;

Fig. 2 is a sectional side view taken on the lines 2—2 and in the direction of the arrows in Fig. 1;

Fig. 3 is a fragmentary front elevation of the machine as shown in the preceding figures; and

Figure 4 is a fragmentary sectional side view of certain of the parts shown in Fig. 2, but illustrating this portion of the mechanism in a different position than that in which it is shown in the preceding figures.

In these views the numeral 5 indicates the base of the machine from which the side walls 6 extend upwardly. Rails 7 are mounted between these side walls and extend transversely of the machine body and a car-

riage 8 is movably mounted upon these rails.

It will be here noted that these rails are positioned adjacent to the rear edge of the machine. Further rails 9 are provided adjacent the forward edge of the machine and are also secured to the side walls thereof. These latter rails extend longitudinally of the machine body and mount between them a carriage 10 which latter occupies a position materially below that occupied by the carriage 8.

As in the application previously referred to, the carriage 8 may be given a vibratory or reciprocating movement transversely of the machine body while the carriage 10 moves longitudinally with respect thereto, these movements being accomplished by any desirable mechanism.

Extending between these carriages is a downwardly inclined deck 11, the upper face of which is divided into a plurality of chutes by having a number of ribs 12 extending upwardly therefrom. The carriage 8 supports a plurality of hoppers 13, by, for example, mounting the latter upon a rod 14 extending lengthwise of this carriage. The chutes provided on the upper face of the deck are divided into groups corresponding in number to the number of hoppers provided, this division being preferably accomplished by utilizing partition members 15 in line with the space extant between the hoppers.

Preferably supported by the side walls 6 is a bar 16 which overlies the upper edges of the hoppers and series of teeth 17 extend from the lower face of this bar into the hopper bodies at a point preferably adjacent the rod 14, it being noted that the supporting of the bar 16 may be effected by having its ends bent downwardly and terminating in forked portions 18 which latter straddle bolts 19 to which they are clamped by wing nuts carried thereby. Each of the hoppers also preferably supports a bar 20 adjacent its forward end and these bars are provided with screw-threaded openings beyond which tooth members or prongs 21 extend into the hoppers, the shanks of these prongs being screw-threaded and engaging with threads of the openings aforementioned.

Upon the upper surface on the carriage 10 a number of receiving compartments are provided. Each of these compartments preferably includes a rear wall 22 and side walls 23, both secured to the carriage 10. Brackets 24 extend upwardly from the side walls and

mount a shaft 25 upon which bell-crank levers 26 are rockingly supported, the inner arms of these levers being slotted as at 27, and slidably accommodating pins 28 to each of which a nest of partition members 29 is attached. These latter partition members correspond in number to the partition members 12 and are arranged in line therewith so that articles moving from the hoppers will pass down the deck and fall into the receptacles on the carriage 10 without diverging from the substantially straight path of travel.

The amount of movement of which the partition members are capable is exemplified in Figures 2 and 4 and should be sufficient to permit of a carton tray 30 being moved into proper position when the nest of partitions has been elevated as in Figure 2. With the bell-crank levers thrown to the position shown in Figure 4 it will be obvious that the lower edges of the partitions will extend into the body of the box and consequently any articles falling between these partitions will be delivered in proper alignment within the box, and, furthermore, the latter will not move relatively to the carriage except when the nest of partitions has been elevated.

In using a device of this character each of the hoppers is filled with a predetermined amount of pins or other articles which are to be assorted. It will be understood that while the hoppers are being filled they are preferably retained in the position indicated in dotted lines in Figure 2, in which position none of the articles will be discharged upon the upper face of the deck 11. An operator may rock one of the bell-crank levers 26 and introduce a carton upon the carriage 10 and subsequently lower the nest of partitions so as to retain the carton in proper position. Thereafter by simply rocking the corresponding hopper around the shaft 14 and to the position shown in full lines in Figure 2 the pins or other articles will be discharged onto the deck and thence into the receiving compartment at the base of which the carton or box is positioned.

It will be appreciated that during all of these operations the carriage 8 is rapidly moving backwards and forwards in a direction transversely of the machine while the carriage 10 is likewise moving in a direction longitudinally of the machine. Incident to the movement of the first carriage the pins which have been thrown into the hoppers in mass formation will gradually come to lie with their axes parallel to each other and their bodies extending towards the delivery edge of the hopper. When the latter has been tilted forwardly they will begin to move towards this delivery edge and incident to the teeth 17 and 21 their alignment with respect to each other and the hopper will be established. In connection with the second-

ary row of teeth or prongs, i. e. the members 21, it will be understood that according to the amount of their projection or retraction the flow of the pins or other articles may be regulated with nicety so that a choking of the various machine parts is thus avoided. As has been illustrated portions of the runways may be enclosed by a cover 31 which, for the sake of convenience, is hingedly mounted so that access may be had to these runways when and if desired. Thus, even if the machine is vibrated to a marked extent the possibility of displacement within the runways will be reduced to a minimum and the articles will be discharged into the receptacles or carriages with their axes parallel to each other and also parallel to the end walls of such receptacle.

Incident to the fact that the latter are moving in a manner before described the articles will quickly assume positions permitting of a maximum amount of the same being packed in one carton.

Finally, it will be appreciated; in order to avoid any likelihood of certain of the pins, etc., falling into the space extant between the frame members which support the nest of partitions and the side walls of the receiving compartments, that protecting strips 32 may be utilized in association with these rear walls.

Thus, among others, the objects specifically before-mentioned are accomplished, and since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent is:

1. An assorting machine for pins and the like, including in combination, a movable hopper, means providing a receiving compartment, means for effecting a delivery of articles from said hopper to said receiving compartment, and means forming a fixed part of the machine and extending into said hopper and in contact with said articles for disposing of said articles in predetermined positions.

2. An assorting machine for pins and the like, including, in combination, a base, vibratory supporting members carried by the base and at different levels, a plurality of hop-

pers carried by one of said supporting members and movable therewith, means providing compartments below said hoppers, means providing fixed chutes extending between 5 said hoppers and receiving compartments, means associated with each compartment structure for removably accommodating a receptacle, and means for normally retaining said receptacle fixed with respect to said 10 compartment structure.

3. An assorting machine for pins and the like, including, in combination, a base, vibratory supporting members carried by the base and at different levels, a plurality of 15 hoppers carried by one of said supporting

members and movable therewith, means providing compartments below said hoppers, means providing fixed chutes extending between said hoppers and receiving compartments, means associated with each compartment structure for removably accommodating a receptacle normally fixed with respect thereto, and independent partition members associated with each of said compartment structures and movable therewith, 20 said partition members normally extending into the receptacles associated with said compartments.

In testimony whereof I affix my signature.

LEVERETT W. TIFFANY.
